(57) **CLAIM**

The ornamental design for a filter, as shown and described.

DESCRIPTION

FIG. 1 is a front, left and bottom perspective view of a filter according to a first embodiment showing our new design; FIG. 2 is a rear, right and top perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a front, left and bottom perspective view of a filter according to a second embodiment; FIG. 10 is a rear, right and top perspective view of FIG. 9; FIG. 11 is a front elevational view of FIG. 9; FIG. 12 is a rear elevational view of FIG. 9; FIG. 13 is a left side elevational view of FIG. 9; FIG. 14 is a right side elevational view of FIG. 9; FIG. 15 is a top plan view of FIG. 9; and, FIG. 16 is a bottom plan view of FIG. 9. The dash-dash broken lines in the drawings depict the portions of the filter which form no part of the claimed design.
